5 Claims. (Cl. 185—37)

This invention is for improvements relating to apparatus for transmitting motion under the positive control of an escapement mechanism.

In a conventional spring driven clock the only normal purpose is to indicate the passage of time. In such case the value of the force applied to a train of wheels is determined by the frictional and other considerations in the operation of the escapement, so that a balance wheel or pendulum is supplied with approximately the correct amount of energy to maintain it in oscillation.

It is common for ancillary duties to be performed by the same mechanism, such as the release of striking mechanism, which usually modify only slightly the force acting on the escapement, and, except in apparatus of special precision, do not detrimentally affect the performance or wear of the escapement.

In certain time-controlled apparatus however, a relatively high power in the driving spring is necessary to perform other duties, as for example in a taximeter, in which the motive force must be adequate for the operation of the fare-computing and registering mechanism and may thus be more than ten times the optimum amount for maintaining the clock escapement in operation. Furthermore, such registration in terms of time is conditional on the prevailing circumstances affecting the vehicle, whereby during the greater part of each journey the whole of the excess driving force in the spring must be restrained by the escapement with consequent difficulties arising from wear and inefficient performance of the clock.

The force required to operate the lever and balance wheel efficiently may for example be two or three grammes on the periphery of the escape wheel, but for the reasons stated it may actually be 20 or 30 grammes at times. Even when the registering mechanism is being driven the value of the force drawn from the clock may vary considerably, so that irregular pressure is exerted on the escapement.

The object of the present invention is to isolate from the escapement all such fluctuations and excess by maintaining a minimum and constant torque on the escape wheel.

The invention thus relates to apparatus, such as for example the clock of a taximeter, for transmitting rotary motion to a torque output shaft under the control of an escapement mechanism, and in which the torque required to operate the escapement mechanism is small compared to the torque (which may be variable) which the apparatus provides at its torque output. The invention provides in such apparatus means for reducing the torque applied to the escapement to a low, constant value appropriate to the small force required to drive the escapement.

2

These means are located between the torque output of the apparatus and the escapement and comprise a spring which is adapted for torsional deflection and which is coupled between a driving and driven member. These 5 are connected respectively to the torque input and torque output ends of the spring just mentioned. The driving member is driven by the torque transmitted in the part of the apparatus between the torque input end thereof and the torque reducing means, and the driven member 10 is driven by the torque of the spring. A stationary member is located in such proximity to the torque input end of the spring that a very small amount of deflection movement of the spring causes the torque input end thereof to bind upon the stationary member with resulting restraint upon the driving member from tensioning the rest of the spring above a predetermined value sufficient only to produce at the escapement mechanism the force necessary to cause that mechanism to function.

A preferred construction, as applied to the clock of a 20 taximeter, is shown in the accompanying drawings, in which:

Figure 1 is a side elevation of a spring driven clock mechanism in which for clarity the gear stages are shown extended in a single plane;

25 Figure 2 is a fragmentary view, drawn on a larger scale than Figure 1, showing the constructional details of the torque reducing means as above referred to of the apparatus; and

Figure 3 is a perspective view of the parts shown in 30 Figure 2.

Referring to Figure 1, a frame 1 supports a spring barrel 2 and a train of wheels and pinions 3, 4, 5, 6, 7, 8, 9, and the escape wheel 10, which is controlled by a lever 11 and a balance wheel 12.

35 At some convenient stage in the train of gearing, for example at the shaft of pinion 5, the spindle may be extended at 13 to provide an output power shaft in order to deliver the force and motion for registration or other purposes as required. At a convenient stage between this output shaft 13 and the escapement, say on the shaft of pinion 7, the automatic control of excess torque is introduced. In Figures 2 and 3 it will be seen that the wheel 8 is not directly attached to the shaft of the pinion 7, but is freely mounted for limited rotation 40 thereon, the pinion having an arm 14 attached which passes through an aperture in wheel 8. Also freely mounted on the shaft of the pinion 7 is a bush 15 which is held against rotation by an arm 16 locating against some portion of the frame 1.

45 The stationary bush 15 and the boss or hub of the moving wheel 8 are adjacent, and of equal diameter. Both are freely encircled by the coils of a spiral spring 17, one end of which is connected to the arm 14 and the other to the wheel 8. The first mentioned end of the spring 17 forms the torque input end thereof and the other the torque output end. The proportions of the spring are such that after a partial rotation has been given to the arm 14 the coils contract upon and tend to grip the bush 15, the tensile torque of the spring 17 at that 50 instant providing the desired torque on the wheel 8. Only the first one or two coils of the spring at the torque input end thereof bind upon the stationary bush 15, the remaining coils remaining free to transmit and maintain the predetermined torque on the wheel.

55 In the process of driving the escapement, the intermittent movement of the wheel 8 momentarily (i.e. at each

escape of the escape wheel) enlarges the diameter of the spring, causing a partial release of the grip thereof upon the bush 15 at the torque input end of the spring, enabling the arm 14 to follow up and restore the grip. In practice the device is so sensitive that less than 1 degree of angular movement of the wheel 8 is sufficient to release the restraint and enable the arm 14 to follow up. The degree of grip of the first one or two coils also becomes automatically adjusted to the driving torque on the shaft of the pinion 7, resulting in a substantially constant torque x on the escapement over a range of at least $20x$ in the applied force.

As the torque control is applied after the point 13 in the gear train from which the registering power is delivered, the device imposes no limitation on the full power of the clock being available at shaft 13 whenever required.

It is only when such registering power is not being fully withdrawn (and therefore tends to increase the torque on wheel 10 above the value x) that the excess is restrained. The value of the restraint at any given instant can be expressed as $R=p-t-x$, where:

p =total available power of clock.

t =power being transmitted externally.

x =power being expended internally to operate the escapement.

The scope of the invention is not limited to the exact constructional form of the invention illustrated in the drawings. For example, the stationary bush 15 may be of a larger diameter internally than the shaft 7 and be fixed directly to the frame 1 in concentric relation to the shaft. In this case the bush would not be guided on the shaft as it is in the construction illustrated in the drawings. Also the cylindrical member constituted by the bush 15 in the construction illustrated may be of tubular formation with the coil spring extending into the tube from one end thereof, the arrangement being such that in the operation of the torque reducing device the spring expands into binding engagement with the bore of the tube, the stationary member being in this sense located around the coils of the spring, whereas in the case of the construction illustrated it is located within the coils of the spring. The particular construction illustrated, however, enables the dimensional and torsional values of the component parts of the device to be predetermined with a high degree of accuracy and at the same time the complete device to be designed as a self-contained unit ready for assembly in a clock mechanism. For this reason the construction illustrated may be regarded as a generally preferred form of the invention.

An arrangement in accordance with this invention is specially suitable in the case of an apparatus for providing power transmission controlled by time measurement within the same piece of apparatus, as in the case described above and illustrated in the drawings of a clock or a taximeter, but it can also be employed in any apparatus where at the torque output end thereof a substantially constant torque or motion is required derived from a source of power applied at the torque input end of the apparatus which is greater in terms of torque transmission than the torque output of the apparatus or which is of non-uniform speed.

What I claim as my invention and desire to secure by Letters Patent of the United States is:

1. Apparatus for developing uniform rotary motion comprising a train of gears, a spring coupled to one end of said train, an escapement coupled to the other end of said train, and means to minimize variations in torque in said gear train at the end thereof adjacent said escapement, said means including two gears of said train mounted coaxially of each other, a stationary barrel mounted coaxially of said two gears, a spiral spring fastened at one end to a point fixed with respect to one of said two gears and at the other end to a point fixed with respect to the

other of said two gears, said spiral spring having some of its coils disposed about said barrel, and means to limit relative rotation of said two gears to a fraction of a revolution.

5. A clockwork motor for driving an apparatus which imposes a fluctuating torque load upon the motor, said motor comprising a train of gears, a main spring coupled to one end of said train, an output power shaft coupled to a gear in said train intermediate the ends thereof, an escapement coupled to the other end of said train, and means to minimize variations in torque in said gear train at the end thereof adjacent said escapement due to fluctuations of load on said power output shaft, said means comprising two gears disposed in said train between said power output shaft and said escapement, said two gears being mounted coaxially of each other, a stationary barrel mounted coaxially of said two gears, a spiral spring having one end fastened at a point fixed with respect to one of said two gears and the other end fastened at a point fixed with respect to the other of said two gears, said spiral spring having some of its coils disposed about said barrel, and means to limit relative rotation of said two gears to a fraction of a revolution.

2. A clockwork motor for driving an apparatus which imposes a fluctuating torque load upon the said motor, said motor comprising a train of gears, a main spring coupled to one end of said train, an escapement coupled to the other end of said train, an output shaft coupled to one of the gears of said train intermediate the ends thereof, and means to minimize variations in torque in said gear train at the end thereof adjacent said escapement, said means comprising two gears disposed in said train between said shaft and said escapement, said two gears being mounted coaxially of each other, a stationary barrel mounted coaxially of said two gears, the one of said two gears remote in said train from said spring having an arcuate aperture therein, the other of said two gears being disposed on the side of said one gear opposite said barrel, an arm fast to said other gear extending through said aperture, and a spiral spring fastened at one end to said arm and at the other end to said one gear, said spiral spring having a fraction of its coils disposed about said barrel.

3. A clockwork motor for driving an apparatus which imposes a fluctuating torque load upon the said motor, said motor comprising a train of gears, a main spring coupled to one end of said train, an escapement coupled to the other end of said train, an output shaft coupled to a gear in said train intermediate the ends thereof, and means to minimize variations in torque in said gear train at the end thereof adjacent said escapement, said means comprising two gears disposed in said train between said shaft and said escapement, said two gears being mounted coaxially of each other, a stationary barrel mounted coaxially of said two gears, the one of said two gears remote in said train from said spring having an arcuate aperture therein and having an axially extending hub thereon adjacent said barrel, the other of said two gears being disposed on the side of said one gear opposite said barrel, an arm fast to said other gear extending through said aperture beyond said hub, and a spiral spring fastened at one end to said arm and at the other end to said one gear, said spiral spring having a fraction of its coils disposed about said barrel and a fraction of its coils disposed about said hub.

4. A clockwork motor for driving an apparatus which imposes a fluctuating torque load upon the motor, said motor comprising a train of gears, a main spring coupled to one end of said train, an escapement mechanism coupled to the other end of said train, said apparatus being external to said train, one of the gears of the train, located between said main spring and said escapement mechanism, having means for coupling the train in driving relation to said apparatus, and means to maintain the

torque in said gear train, at the end thereof adjacent said escapement mechanism, substantially constant as the torque load upon the motor, imposed thereupon by said apparatus, fluctuates, said means including a first gear, a second gear mounted coaxially of said first gear and in driving relation thereto, said first and second gears forming successive gear elements in said gear train and being disposed in said gear train between said one gear and said escapement, a stationary barrel mounted coaxially of said first and second gears and a spiral spring fastened at 10 one end to a point fixed with respect to said first gear and at the other end to a point fixed with respect to said

second gear, said spiral spring having some of its coils adjacent its first mentioned end disposed about said barrel so as alternately to bind thereon and unbind therefrom with motion of said escapement mechanism.
